UNITED STATES PATENT OFFICE.

MAURICE SAMBURG, OF SEAGATE, NEW YORK, AND JULIUS C. HOCHMAN, OF PASSAIC, NEW JERSEY.

COMPUTING ATTACHMENT.

Application filed December 11, 1919, Serial No. 344,239. Renewed March 10, 1926.

Our present invention relates to computing machines and more particularly to machines for performing the operation of addition and preferably also that of subtraction.

5 An object of the invention is to provide a mechanism of the above type which shall be compact, light and simple in construction, yet reliable in action under hard usage.

Another object is to provide a computing 10 mechanism of the type referred to, of such construction that it can be readily associated with a common form of printing mechanism, such, as for instance, an ordinary typewriter, to cause the latter to print the 15 numbers concurrently with the actuation of the computing mechanism, and certain features of the invention reside in a novel combination of our computing mechanism with such typewriter or other printing mechanism. 20

Another object is to provide a computing and printing machine of flexible character to suit various kinds of work and which shall not require special forms, and which shall 25 more particularly be susceptible of performing all or any combination of the following functions: making vertical or cross additions, printing anywhere on the sheet, adding dollars, weights, quantities or any other 30 units, punctuating the numbers as desired and making in one operation any number of carbon copies, including the sums figured.

Another object is to provide a computing mechanism which when associated with any 35 ordinary typewriter will not impose on the latter any strain or force greater than those imparted to it in ordinary operations for corresponding purposes and will still allow said typewriter to be operated at all times 40 without actuating any part of the computing machine and through all functions, identically as though the computing mechanism were not attached thereto.

Another object is to provide a computing 45 mechanism which when attached to a typewriter will allow the typewriter to be used on the ordinary "drophead" type of desk, without interfering with the closing thereof, and which will not necessitate chopping into the desk in any way in order to obtain this 50 result.

In a preferred embodiment for carrying out the above objects, we provide a complete self-contained computing machine of dimensions and arrangement such that it can read-

ily be mounted on the frame of many of the common makes of typewriters, above and free from interference with the normal operation of the typewriter keyboard, the above mentioned printing by the typewriter concurrently with the arithmetical operation by the computing mechanism being effected by a disposition of keys or other actuating members of the latter, at such intervals that when the device is mounted upon the typewriter, the number key members of the latter are in the path of operation of the former. The typewriter platen can, therefore, be shifted at will in the course of addition, either laterally or circumferentially to suit the particular form being used and the typewriter keyboard may be operated to print any characters without interference with the accuracy of the arithmetical operation performed by actuation of the computing attachment. 60 65 70 75

Our computing attachment although preferably employed in the relation above set forth may be used to advantage apart from a typewriter in which event the results of computation are readable but neither the numbers nor the sums are printed. 80

These and other objects, which will become evident as the description progresses, are attained by the novel construction, arrangement and combination of parts hereinafter described and shown in the accompanying drawings forming a material part of this disclosure, and in which:

Figure 1 is a fragmentary plan view of 90 a standard typewriter showing the calculating attachment in operative position.

Figure 2 is a front elevational view of the same.

Figure 3 is a fragmentary transverse vertical sectional view of the typewriter and side view of the applied mechanism constituting the invention. 95

Figure 4 is an enlarged longitudinal sectional and plan view of the mechanism, the 100 casing being removed.

Figure 5 is a front elevational view of the same.

Figure 6 is a transverse sectional view taken on line 6—6 of Fig. 4. 105

Figure 7 is a similar view taken on line 7—7 of Fig. 4.

Figure 8 is another like sectional view taken on line 8—8 of Fig. 4.

Figure 9 is a perspective view of the sup- 110

port plate forming the rear of the attachment casing.

Figure 19 is a perspective view of one of the key bars in detail.

25 Figure 20 is a plan view of a typewriter showing a modified form of computing attachment.

Figure 21 is a side elevational view of the casing used in connection therewith.

30 Figure 22 is a perspective view of a key bar applied directly on the casing.

Figure 23 is a perspective view showing the type of detachable key bar arranged over the typewriter.

35 Stated in general terms the invention consists of a series of accumulators or numeral wheels operable in a casing secured to the front of a typewriter above the key board, where it is convenient to access, each of the wheels being independently actuated by individual key depressions and also by the accumulating devices operating one wheel from another.

40 Each of the actuating keys is provided with a bar engaging the key bar of the typewriter so as to cause depression of the same and print characters corresponding to the numeral key depressed and the number added or subtracted as indicated on the numeral wheel.

45 50 Referring now more particularly to the drawings in detail, the numeral 50 designates in general a typewriter, as indicated, although any standard type of machine can be used, having all the usual parts and functions.

55 Attached to the front of the typewriter, above and approximately central with its key board, is a plate 51, having arms 52 rigidly secured by screws 53 to the machine.

60 65 Formed in the front of the plate 51 are ten vertical grooves 54, the same registering with the numeral key levers of the typewriter, including the small letter "L", ordinarily used as the figure 1, and disposed in the second row of the bank of keys, while

the others, including the "0" or zero and figures 2 to 9 inclusive, this arrangement necessitating the two slots at the left of the plate being placed relatively close together.

A narrow strip or bar 55 is secured over 70 the plate 51, at its lower marginal edge, crossing all of the several grooves and acting as a keeper for the several bars 58 slidable in the grooves.

All of the bars 58 rest at their lower ends 75 on the numeral key levers as best shown in Figs. 2 and 6.

Attached to the front of the bars 58, are angles 59 their extending elements being surmounted by key buttons 60, the same being 80 positioned convenient of access and without interference to other parts when operated.

These bars each contain an elongated slot 61 midway in their length, and terminate in outturned right angled lugs 62. 85

A thin metallic casing, generally designated by the numeral 65, is formed with a level horizontal top 66, blending into a curved front upper portion 67, merging into the rearwardly inclined front 68 leading to the bottom plate 69, parallel with the top; the ends 70 of the casing, which is fixed to the upper portion of the plate 51, being extended outwardly beyond the main central portion for purposes further on apparent. 95

Fixed to the rear plate 51, adjacent the end walls of the casing are a pair of rigid plate brackets 71 and 72, respectively right and left, the same extending into the projecting portions 70 of the casing. 100

Revolutely mounted and extending between the brackets, at their upper front portions, is a shaft 75 below which is a rod 76 held in rigid engagement to the brackets at each end by clamp nuts 77. 105

Another rod 78 fixed in the brackets extends longitudinally through the casing, and a second shaft 80 is revoluble in the brackets, the same extending through the plate 71 to the wall of the casing and shiftable to the opposite side by mechanism later described. 110

A pair of spur gears 81 and 82 are set screwed by their hubs to the ends of the shaft 75, adjacent to their respective brackets, preventing the shaft from moving endwise. 115

Meshing with these gears is another pair of gears 83 and 84, loose on the ends of the shaft 80 so as to rotate on the shaft, and permit it to slide through. 120

Fixed rigidly on the shaft 80 are a pair of relatively wide faced pinions 85 and 86 engageable with a pair of racks 87 and 88 when the shaft is moved to the right, and with another pair of racks 89 and 90, when moved to the left, this latter pair of racks being at the front and to the left of the first named pair. 125

Both pairs of racks are secured at the ends of a stepped operating plate 92 guided by 130

elongated slots 93 formed in the outer rack elements 89 and 90, through which passes the shaft 80 which also limits the vertical movement of the plate, those rack elements 5 containing recesses 94 clearing the rod 78 when the plate is drawn down.

Intermediate between the plates 92 and 51 is a back spacing plate 95 having its angular and downwardly extending ends formed in 10 to racks 96 and 97 directly engaging the gears 81 and 82 transmitting motion to the shaft 75 upon the depression of the error key 98, (the same being secured to a projection 99 formed centrally at the top of the plate 95) or any numeral key.

Another projection 100 from the lower edge of the plate is outturned and has secured to it a tension spring 101 attached to a pin 102 at the top of the casing, the same 20 normally holding the plate 95 in raised position and also the plate 92 which is closely adjacent and rests upon the outturned projection 100.

The upper edge of the plate 92 has formed 25 upon it a series of nine steps 105, with which the bent ends 62 of the bars 58 are adapted to make contact, all of these several ends resting on the upper edge of the plate 95 and extending to the front so as to engage 30 the steps of the plate when depressed.

Formed in the lower portion of the plate 92, at spaced intervals to register with the centers of the bars 58 are slots 106 differing in extent and thereby limiting the distance 35 downward which the plate can move in accordance with the key depressed, and thereby guarding against over-travel due to inertia.

Secured on the rod 78 are a plurality of 40 spacing sleeves 107 having between them detents 108 normally drawn forward into an inoperative position by springs 109 and provided with arms 110 engaging in the slots 61 of the key bars 58, so that as the latter 45 are depressed, the detents are moved to engage in the slots 106 limiting the downward stroke of the plate 92 according to the value of the key depressed.

The shaft 80 is shifted lengthwise in its 50 bearings, causing either side of the pinions to engage with the vertical racks whereby the shaft is rotated in either direction as desired by depression of the numeral keys, in the following manner.

55 A slot 111 having a raised central portion or lug 112 is formed through the front element 67 of the casing, at the left hand side and extending outwardly therethrough is a lever handle 113 by which the shift can be 60 made, causing the apparatus to add or subtract at will.

The lever 114 with which the handle is formed, is pivoted on a bracket 115 attached 65 interiorly of the casing and is provided with a fork 116 or its equivalent, contiguous

to the shaft 80 and adapted to contact with the pinion 86 on one side and with a hub 118 fixed to the shaft 80 and having an arm 119 extending at a right angle to the right.

A ratchet wheel is secured by its hub 121 70 to a sleeve 126 rotatable on the shaft 80 and at the opposite end of the sleeve is secured an actuating gear 128 having its teeth bevelled to facilitate engagement with the teeth of the numeral wheels as hereinafter described, the gear, sleeve and attached parts being held from movement on the shaft 80 by a fork 129 secured within the casing.

The arm 119 carries a pawl 124 cooperating with the ratchet wheel to transmit 80 driving impulse thereto for addition, and it further carries a second driving pawl 125 which will be substituted for the first pawl to transmit the torque in the reverse or subtraction operation, as will appear more fully 85 in the description of the operation below.

The totalizer as a unit is mounted on a shaft 75 and consists of frame comprised of a bar 130 having angular arms 131 containing openings 225' for the tube 225, other 90 openings 76' being formed in the arm extensions for the rod 76 so that the frame is supported but free to move on the shaft and rod.

Secured to the back of the frame bar 130 is 95 a toothed rack 132 the same extending to the left of the frame and engageable with a pinion 133, see Fig. 8, fixed on a spindle 134 rotatable in a bracket 135 and also in an opening 134' formed in the back plate 51. 100

The spindle 134 extends across the plate 95 by reason of a slot 136 extending in from the top and also the plate 92 by a similar recess 137 formed in the upper edge of an offset portion 92', this offset forming a pocket 105 in which is positioned a ratchet 138 operated by a pawl 139 pivoted on the inner face of the plate 95 and normally held against a pin 140, set in the plate by a spring 141, thus as the back plate 95 is depressed and 110 moves upward again, means are provided for moving the totalizer toward the left one space automatically.

An offset extension 142 is fixed to the arm 115 at the right of the carriage acting as a rear prolongation of the same, this extension and arm limiting the movement of the totalizer to the right as will now be shown.

Fixed in the casing, near the right hand end is a vertical bracket 145, its upper end 125 being turned outwardly closely adjacent to the shaft 75 and has attached to it one end of a coiled tension spring 147 encircling the shaft and attached at its other end to the totalizer carriage in such manner as to normally draw it to the right of the casing.

Another like bracket 148 is fixed at the rear of the casing registering with the bracket 145, and mounted in these brackets is a 130

rod 150 transversely to and immediately below the shaft 80.

Pivoted on this rod (see Fig. 17) are a plurality of levers 151, 2, 3, 4, 5 and 6 extending to the left and of different lengths, the same acting as stops to engage the totalizer carriage as drawn by the spring 147.

Another bracket 158 in the casing supports a comb or slotted guide 159 through which the levers 151, etc. freely pass, the levers being supported by flat springs 160 extending to the left from an angle carried by the comb element 159 as can be seen in Figs. 5 and 18, the free ends of the levers being normally raised as indicated.

The longest and rearmost lever 151 is formed with a raised arm 161 extending over the upper edges of the adjacent levers 152 and 153 and is provided at its end with an upturned slotted projection 171.

In a like manner the lever 152 has a raised arm 162 extending over the levers 153 and 154, terminating in a slotted projection 172 and has at the rear a low arm 182 resting on the lever 151.

The third lever 153 has a raised arm 163 with its slotted projection 173 extending over the shaft 80, and a low rear extension 183 on the levers 152 and 151.

The lever 154 has a raised arm 164 over the lever 155 and shaft 80, a slotted projection 174 and a low arm 184 on the levers 151, 152 and 153.

The lever 155 has a raised arm 165, a projection 175 and two low arm sections 185 and 185' normally resting respectively on the levers 151, 152, 153 and 154.

The outermost and shortest lever 156 has a raised arm 166, a vertical slotted projection 176 and two low arm sections 186 and 186' extending respectively on the levers 151, 152 and 153 and also on the levers 154 and 155. A lug 187 extends upward from the edge of the front lever 156 and acts as a stop for the carriage in the highest decimal position.

Extending through slots in the cover plate 66 of the casing are a plurality of stems engaged separately with the several projections and provided with finger pads 191, 192, 193, 194, 195 and 196, corresponding to the several levers, each of the pads bearing indications of decimal values, as tens, hundreds, thousands, etc., all of the several stems containing slots engaging in the corresponding slots of the projections in such manner as to prevent lateral motion in any direction while the springs 160 return the pads to normal position after depression; the pads being arranged in staggered relation and readily accessible, (see Figs. 1, 2 and 3).

Slidably mounted around the rotatable shaft 75, between the totalizer frame sides 131, is a tube or sleeve 225 upon which is

engaged a plurality of numerals wheel units arranged closely adjacent side by side. Each of these units consists of a gear 226 having peculiarly shaped lapped teeth engageable with the actuator gear 128.

Also engaged with the teeth of the gears 226 are bent flat detent springs 227, fixed at their outer rear ends to a plate 228 secured rigidly to the frame element 130 on its inner side.

Formed with or secured to the plate 228 are projections 230 having bevelled forwardly extending cam ends 231 disposed between each of the totalizer units, as best seen in Figs. 13 and 15, the points of the projections closely approaching the teeth of the ratchet wheels 232 adjacent the gears 226, but secured to the adjoining wheels of the next higher denomination by rivets 233.

These rivets pass through the wheel centers 235, enclosing between them and the ratchets 232 the gears 226 and spring elements 236, having bent finger portions 237 partially contained in recesses 238 formed in the wheel centers 235, the ends of the fingers 237 normally clearing the teeth of the ratchet wheels 232 but engageable in the spaces between the teeth when rotated into contact with the bevelled cam surfaces 231, which depress the finger and cause a carrying action of one tooth of the ratchet wheel, or in other words, moves it one tenth of a revolution in which ever direction the numeral wheel unit carrying the finger may be moving, thus performing the function of carrying in addition or subtraction.

Secured circumjacent to the wheel centers 235 are bands 239, on which are displayed ten numerals 250, from 0 to 9 inclusive which are disclosed through appropriate openings 252 formed through the casing 65 in such position as to be readily observable.

In operation, the device having been securely attached to the frame of a typewriter it will be seen that none of the functions or usefulness of the latter are interfered with, and no room occupied that is used for other purposes.

It will be further apparent that the attachment presents no obstacle to the full and free access to the various keys of the typewriter, nor is the attachment objectionable in appearance.

Let it be supposed that the numeral wheels of the totalizer are all set at 0 and it is desired, as in the body of a letter or bill, to set up thirty-one thousand dollars and forty-six cents, \$31,000.46, and add to it five hundred dollars and twelve cents, \$500.12.

The items of the letter or bill are written upon the paper sheet, placed on the platen of the typewriter, by operating the keys in the usual manner, when this has been done and the column, for listing amounts brought

into position for printing the \$ key of the typewriter is depressed and the sign written.

Thereupon the tabular key 196, representing millions, at the right of attached mechanism, is depressed, causing the totalizer to be drawn by the spring 147 against the stop 187 so that the numeral wheel registering millions is brought into mesh with the gear 128.

The numeral key 60 representing 3 of the attachment is now depressed, its stem normally lightly resting upon the corresponding key lever of the typewriter, causing the lever to be depressed, thereby writing the numeral 3 on the sheet adjacent to the right of the dollar sign and causing the platen to shift one space to the left.

Simultaneously the overhanging lug 62 of the attachment key causes the back space plate 95 to be moved down, the lug ultimately contacting with its corresponding step on the plate 92, drawing it down, and by reason of the equalizing racks 87 and 90 at its ends engaging the pinions 85—86, which transmit rotary motion to the shaft 80, rigidly carrying the arm 119, whereby the pawl 124 will rotate the sleeve 126 carrying the actuating gear 128 meshing with the wheel of the totalizer, then in view and turning it to disclose the numeral 3. In the downward movement of the back plate 95 the racks 96 and 97 rotate the loosely mounted gears 83 and 84 respectively, and since these gears mesh with the gears 81 and 82 respectively, and the latter are rigid upon the shaft 75, the movement of the back plate 95 will be equalized, that is, the plate will have an accurate movement of translation without tilting or cocking, thereby eliminating the likelihood of binding or jamming.

When the attachment numeral key is released, and the back space plate 95 is raised by the spring 101, which also raises the stepped plate 92, the pawl 139 carried on the back space plate, engages the ratchet wheel 138, rotating the pinion 133, which transmits motion through the rack 132 to the totalizer, moving it one space to the left and disclosing the next adjacent numeral wheel.

In like manner the attachment numeral key 1 is depressed, its stem engaging the typewriter key lever for the small alphabetical character L which prints 1, moving the next wheel in the totalizer to register in accordance, and also to move another space to the left.

The next operation is to use the typewriter key bearing the comma sign and then continue the use of the attachment keys for the next three figures 2, 6 and 2, then inserting a period or decimal point, by the typewriter and completing the motion by the keys of the attachment.

The second number viz:—\$500.12 is similarly written by the use of the attachment keys, except for the signs used, but the sum of the two numbers will now appear upon the totalizer and can be transferred to the paper sheet by the keys of the typewriter.

For the operation of subtraction, the lever-handle 113 is first moved toward the right, urging the operating shaft 80 toward the left, disengaging the gears 85 and 86 from the racks 87 and 88 respectively and bringing them into meshing engagement with the reverse racks 89 and 90 respectively. The arm 119 which is rigid with the operating shaft will, of course, be shifted therewith toward the left, moving the pawl 124 laterally out of engagement with the ratchet 120 and into engagement with the hub 121 and moving the subtraction pawl 125 from the hub 122 into cooperation with the ratchet 120, so as to transmit the torque in the reverse direction.

From this point, the operation proceeds substantially as above described, it being understood that in the downward movement of the operating plate 92, racks 89—90 will cause a reverse rotation of the gears 85 and 86, thereby causing all of the operations above described, to be performed in a reverse direction for subtraction.

In case an incorrect tabulating setting has been made, say that the totalizer has been shifted to 10,000, where only 100 is required, it is merely necessary to depress the error key twice in succession, to thereby step the totalizer toward the right, first to the 1000 setting and then to the 100 setting. Upon each return movement of the operating plate 95 of which the error key 98 is a part, the pawl 139 will rotate the corresponding ratchet 138 and thereby drive the pinion 133 which by reason of its cooperation with the rack 132 will cause the return movement of the carriage.

Due to the absence of any mechanical linkage connecting the computing mechanism to the typewriting platen, flexibility of operation is accomplished. The machine will add figures arranged either vertically or horizontally with punctuation to suit the work being done.

The computations are mechanically correct, even if the listings are not in registration, while the use of the decimal points and other divisions of the numbers are readily made without confusing the showings on the totalizer.

It may also be pointed out that the inertia devices consisting of the spring actuated element 108, operated by the slots 61, of the keys, prevent over movement of the stepped plate and therefore of the totalizer in a manner which will be clearly evident.

In the modified form of attachment, shown in Figs. 20 to 23, inclusive, an inde-

pendent casing generally designated by the numeral 300 is formed with a forwardly extending base portion 301, supported upon feet 302 resting on the same level as the feet 5 of the typewriter 50, to which it is removably attached by the clamp connection 303.

The interior mechanism is of substantially the same construction except that the key stems 305, carrying the numeral pads 306, 10 have extensions 307 containing openings 308 adapted to receive the tapered ends 309 of the lever bar 310 which may be firmly pressed, these bars having downward vertical extensions 311 adapted to normally 15 lightly rest upon the key levers of the typewriter, and subject to depression by the pads 312 mounted on offset vertical extensions 313, so that the pads are arranged to the rear of the key-board of the typewriter.

20 In this adaptation the machine may be used by itself as a calculating instrument or connected with a typewriter in a moment of time and then used as in the foregoing description.

25 The foregoing description is to be regarded as descriptive and explanatory rather than restrictive, as obviously many minor changes may be made within the scope and spirit of the appended claims.

30 Having thus described our invention, what we claim as new and desire to secure by Letters Patent, is:—

35 1. A calculating mechanism comprising a casing engaged with a typewriter, a totalizer movable in said casing, means for rotating the wheels of said totalizer and operating the numeral keys of the typewriter simultaneously, independent means for shifting said totalizer, and a plurality of shiftable 40 tabulating stops normally in the path of displacement of the totalizer and means for setting said stops to dispose said totalizer at will for the number of decimal places of the number to be set up.

45 2. A calculating mechanism comprising a casing engaged with a typewriter, a carriage movable in said casing, a totalizer therein, means for actuating said totalizer and the numeral keys of the typewriter simultaneously, means for moving said carriage, a plurality of overlapping stops limiting the carriage movement, said stops being independently operable, and an error key for effecting the return movement of the carriage to its initial position.

50 3. A calculating mechanism comprising a casing, a totalizer movable therein, a spring for moving said totalizer in one direction, a plurality of independent pivoted lever stops for limiting the travel of said totalizer, and mechanism for automatically advancing said totalizer, step by step against the pull of said spring.

55 4. A calculating mechanism comprising a casing, a totalizer movable therein, said

totalizer containing a plurality of numeral wheels, a single actuating gear engageable with any of said numeral wheels, means for maintaining said actuating gear in a fixed position, a plurality of keys having different 70 numeral values by which said actuating gear is proportionately rotated, and an inertia device for each key preventing its over-movement.

5. A calculating mechanism comprising a 75 casing, a totalizer movable therein, said totalizer containing a plurality of numeral wheels, an actuating gear independently engageable with said wheels, a sleeve on which said actuating gear is fixed, a shaft 80 in said casing on which said sleeve is rotatably mounted, a ratchet wheel on said sleeve, an arm fixed on said shaft, oppositely disposed pawls carried by said arm, means for engaging either of said pawls with said ratchet wheel whereby it is turned in either 85 direction, a plurality of numeral keys, and intervening mechanism for rotating said shaft a predetermined amount.

6. A calculating mechanism comprising a 90 casing, a totalizer movable therein, a plurality of numeral key levers, a single plate having a step for each lever whereby it is depressed a definite and different distance, a pair of oppositely disposed equalizing 95 racks fixed at the ends of said plate, a shaft in said casing between said opposite rack pairs, pinions on said shaft, means for shifting said pinions to engage with either of said rack pairs, and mechanism for transferring the rotary motion of said shaft to the wheel of said totalizer.

7. A calculating mechanism comprising a casing, a shaft mounted longitudinally therein, a sleeve slideable on said shaft, a carriage fixed on said sleeve, said carriage supporting a totalizer, tensional means for drawing said carriage in one direction, a rack extending from said carriage parallel with said shaft, a spindle journaled transversely in said casing, a pinion fixed on said spindle engaging said rack, a ratchet wheel on said spindle, a key movable vertically in said casing, means for raising said key after depression, and a spring actuated pawl carried by said key engaging said ratchet wheel on its upward movement whereby said carriage is moved step-by-step in a direction opposite said tension means.

8. A calculating mechanism comprising a 120 casing, a shaft mounted longitudinally therein, a sleeve slideable on said shaft, a carriage fixed on said sleeve, said carriage supporting a totalizer, tensional means for drawing said carriage in one direction, a rack extending from said carriage parallel with said shaft, a pinion engaging said rack, a plate movable vertically in said casing, an escape- 125 ment key on said plate, means for returning said plate to normal position, equalizing de- 130

vices at the ends of said plate for assuring a pure movement of translation thereof, and means carried by said plate adapted through intervening mechanism to actuate said pinion 5 whereby said carriage is moved against said tension means.

9. A calculating mechanism comprising a casing, a totalizer movable therein, a spring for moving said totalizer in one direction, a plurality of independent pivoted lever stops 10 limiting the travel of said totalizer, said stops being graded in length progressively in amount equal to the distance between the numeral wheels of said totalizer, individual key means for depressing the first or longest stop, or any number of said stops 15 in sequence collectively, and resilient means for returning said stops to their initial position after depression.
10. A calculating mechanism comprising a casing, a totalizer movable therein, a spring for moving said totalizer in one direction, a plurality of independent pivoted lever stops 20 limiting the travel of said totalizer, said stops being graded in length progressively in amount equal to the distance between the numeral wheels of said totalizer, individual key means for depressing the first or longest stop, or any number of said 25 stops in sequence collectively, a lug on the last or shortest stop acting as a fixed limit, guides for said stops, and a spring for each stop adapted to return the stops to operative 30 position when free.
11. The combination with a calculating machine having a totalizer and numeral keys for the operating thereof, of a typewriter having numeral keys of standard 35 construction, recessed lateral lugs formed with the stems of the calculating machine 40 keys, and independent offset keyed levers of suitable length adapted to engage firmly in the recess of the lugs, their keyed ends making loose but operative contact with the 45 corresponding numeral keys of said typewriter.

12. A calculating mechanism comprising a casing, a longitudinal shaft therein, a totalizer carriage slidable on said shaft, tensional means for drawing the carriage in one direction, a rack on said carriage, a pinion 50 engaging said rack, said pinion being normally free to rotate, and key operated means for communicating motion to said pinion 55 thereby retracting said carriage.

13. A calculating mechanism comprising a casing, an operating shaft and a totalizer shaft disposed parallel longitudinally in 60 said casing, both shafts being rotatable and said operating shaft being slidable, gears fixed at the ends of the totalizer shaft, other gears loose on said operating shaft, a pair 65 of racks engaging the last named gears, a plate connecting said racks, means carried

on said plate for moving said totalizer laterally, and a plurality of means for operating said plate, said rack and gear connections acting as an equalizer for said plate to assure a pure movement of translation thereof.

14. A calculating mechanism comprising a casing, a totalizer movable therein, a plurality of keyed levers, a plate engaged at spaced intervals by said levers, equalizing devices at the ends of said plate, a single 75 resilient means for maintaining said plate in a raised position, a second plate having stops upon its upper edge spaced in conformity with said key levers and contactable therewith when the levers are depressed, 80 guides recesses in the lower edge of said stepped plate the slots extending different distance therein and registering with said key levers, individual spring actuated detents aligned with said recesses, means in 85 said key levers for moving said detents into said recesses and means at the ends of said stepped plate for actuating said totalizer upon the depression of said key levers.

15. A totalizer comprising a supporting 90 carriage, a plurality of numeral wheel units of composite construction each independently rotatable, spring carrying fingers forming part of each unit, said fingers being engageable when depressed with notches in 95 the adjacent wheels, and double faced cams fixed on said carriage adapted to cause said fingers to operatively engage with the adjacent wheels when passing said cams in either direction thus forming a carrying 100 means therebetween both for addition and subtraction.

16. A calculating mechanism comprising a casing, a totalizer operable in said casing, means for rotating the wheels of said totalizer and operating the numeral keys of a typewriter simultaneously, an independent escapement for said totalizer, and means operable by a manipulation with one finger to set the totalizer for the number of decimal places of the number to be set up.

17. A calculating mechanism comprising a casing engaged with a typewriter, a carriage movable in said casing, a totalizer therein, means for rotating the wheels of 115 said totalizer and operating the number keys of the typewriter simultaneously, tabulating keys carried by said casing, each operable by a direct one finger thrust to selectively shift the totalizer to tabulating position and 120 escapement means to return the totalizer toward units' position after digit operation.

18. A calculating mechanism comprising a casing engaged with a typewriter, a totalizer associated with said casing, a carriage 125 movable in said casing, means for rotating the wheels of said totalizer and operating the numeral keys of said typewriter simul-

- taneously, a spring urging said carriage to the outermost tabulated position thereof, tabulating stop means determining the various tabulated positions of the carriage, said stop means normally retaining the carriage in units' position, tabulating keys on said casing each operably by a single one finger thrust to selectively determine the effective position of the stop means for tabulation.
- 19 and escapement means to automatically return the carriage in a step by step action.
19. A calculating machine comprising a casing engaged with a typewriter and mounted inobtrusively to freely expose the typewriter key board, and to extend free from the path of displacement of the operating mechanism of the typewriter, a totalizer operable in said casing, a single tractive means for said totalizer and controllable stop means for setting the totalizer in appropriate position for the decimal places in the number to be set up.
20. A calculating attachment for a typewriter comprising a casing secured to the frame of the typewriter, a totalizer in said casing, escapement means for said totalizer distinct from the typewriter escapement, an actuating gear engageable with any of the wheels of said totalizer, key operated means for driving said gear simultaneously with printing numbers on the typewriter, and means for shifting the direction of rotation of said gear so that either addition or subtraction may be accomplished on said totalizer.
21. A calculating machine comprising a casing engaged with a typewriter, a totalizer operable in said casing, tractive means for urging said totalizer in one direction and escapement means distinct from that of the typewriter for returning said totalizer step by step to its initial position.
22. An adding mechanism comprising, in combination, a key operated totalizer, an escapement controlling the decimal actuation of said totalizer, a plate moved through a common stroke by the actuation of each key and a pawl carried by said plate for actuating the escapement in each key stroke.
23. In an adding mechanism in combination, a key board, a totalizer actuated therefrom, said totalizer having a carriage provided with a rack, a pinion meshing with said rack, an escapement mechanism operatively interposed between the key board and the totalizer, said mechanism including a pawl element for operating the pinion, one step for each key stroke for the step by step return of the totalizer from tabulated position.
24. A combined typewriter and computing machine comprising a typewriter element, a computing element including a casing affixed to the frame of the typewriter and having a distinct key board, key bars connected to the individual elements of the key board, each bar normally sustained upon the typewriter key lever of corresponding number.
25. A calculating machine comprising a casing carried by a typewriter, a totalizer operable in said casing, and keys for actuating said totalizer, said keys being normally supported loosely and non-interferingly directly upon the upper edges of the numeral key levers of the typewriter.

In testimony whereof we have signed our names to this specification.

MAURICE SAMBURG.
JULIUS C. HOCHMAN.
